UNITED STATES PATENT OFFICE.

THEODOR WINESTOCK, OF STUTTGART, GERMANY, ASSIGNOR TO OTTO CHARLES
WINESTOCK, OF PERKINSVILLE, VERMONT.

SPARK-PLUG.

No. 919,276.

Specification of Letters Patent.

Patented April 20, 1909.

Application filed April 30, 1908. Serial No. 430,131.

To all whom it may concern:

Be it known that I, THEODOR WINESTOCK, a subject of the Emperor of Germany, residing at Stuttgart, Würtemberg, Empire of Germany, have invented a new and useful 5 Spark-Plug, of which the following is a specification.

This invention has reference to improvements in spark plugs for explosive engines, 10 and its object is to provide a means whereby a spark plug may be inserted or removed at will from the explosion or ignition chamber of the engine without the use of any tools.

By the present invention the spark plug is 15 made in two parts, one part being practically constantly fixed in the walls of the ignition chamber, and the other part carrying both spark terminals and readily removable from the fixed part, while provision is made where- 20 by the two parts may be locked together removably, but so as to produce a gas-tight joint at the point of union. The locking means employed is so constructed that when the removable portion of the spark plug is 25 seated in the fixed portion thereof there is little or no tendency toward the accidental unseating or loosening of the removable section of the plug in its seat by any forces except those purposely applied. Furthermore, 30 by providing the removable member with both spark terminals it is possible to thor- 35oughly inspect and cleanse or repair the vital portions of the spark plug without the necessity of unscrewing the member applied to the threaded passage leading to the interior of the ignition chamber, as is necessary with the ordinary spark plugs, or those in which one terminal only is removable.

The invention will be best understood from 40 a consideration of the following detail de- 45 scription taken in connection with the accom- 50 panying drawings forming a part of this specification, in which drawings—

Figure 1 is a longitudinal section of the 45 spark plug, and Fig. 2 is an elevation of the same.

Referring to the drawings, there is shown 50 a member 1 in the general form of a cylind- 55 2 externally screw-threaded to enter the screw-threaded passage usually provided in the walls of the ignition chamber of an explosive engine for the introduction of a spark plug. The member 1 is provided with a 55 polygonal portion for the reception of a

wrench or other means of screwing the member 1 into the ignition chamber or of unscrewing it therefrom. That end of the member 1 remote from the neck 2 is formed with entering slots 3 curved until the inner 60 ends of these slots are substantially concentric to the longitudinal axis of the body 1. The interior of the member 1 is formed with a cylindrical portion 4 at the slotted end, and a smaller cylindrical portion 5 coincident 65 with the threaded neck, and between these two portions there is a conical section 6 of decreasing diameter toward the neck 2. Both ends of the cylinder are open.

The movable member comprises a body 70 portion 7 shown as slightly longer than the fixed member 1 and conforming in exterior contour to the shape of the member 1. At diametrically opposite points the body 7 of the movable member has screwed into it ra- 75 dially-projecting pins 8, each of which is pro- 80 tected by an insulating cap 9 constituting a handle by means of which the movable mem- 85 ber may be manipulated. The pins 8 are of such diameter and the insulating caps or han- 90 dles 9 are so spaced from the body 7 that the pins 8 may be caused to enter the open ends of the slots 3, the said slots being diamet- 95 rically disposed in the cylindrical or fixed member 1 and then by turning the body por- 100 tion 7 on its longitudinal axis, the said body portion will be forced into the member 1 until the intermediate conical portion 10 of the body 7 is in intimate contact with the con- 105ical seat 6, the parts being locked together by the concentric portions of the slots 3.

Extending longitudinally through the body 7 of the movable or removable member is a central bore 11, and this bore is counter- 95 bored, as indicated at 12, for a portion of its length from the smaller end of the body por- 100 tion. The central bore 11 has in it an insu- 105 lating sleeve 13 extending beyond the wide end of the body portion 7, and also at the other end entering the counterbore 12. Within the said counterbore is another insu- 110 lating member 14, and beyond the wide end of the body portion 7 is insulation 15. The insulating member 14 is of sufficient length to extend beyond the small end of the body portion 7.

Extending centrally through the insulating members 11, 14 and 15, is a metallic rod 16 terminating at one end in a head 17 and at the other end in a screw-threaded portion 18. 110

Between the head 17 and the insulating member 14 there is confined a disk 19 having on one side an annular crown of teeth 20 directed toward the end face 21 of the small end of the body portion 7. The screw-threaded end 18 of the rod 16 receives a number of nuts 22 and also a thumb nut 23 such as is commonly employed upon binding posts.

10 The insulating members 11, 14 and 15 may be formed of any suitable insulating material capable of standing up under comparatively high electric pressures, while the insulating sleeve 14 should also be of refractory material. An excellent insulating material, which is also highly refractory, is mica and the insulating members 14 and 15 can, therefore, be made up of superposed washers of mica while the sleeve 11 may be made up of 20 mica composition or mica disks. When the insulating members are made of suitable insulating material other than mica they may be suitably molded into shape, and the sleeve 11 may be inset into both the members 14 25 and 15 to prevent danger of leakage of current at the joints. In the case of mica the insulating material may be suitably built up of disks of proper shape.

One circuit terminal is connected to the 30 rod or stem 16 by clamping the end of the conductor between the thumb nut 23 and the outer one of the nuts 22, the said nuts 22 serving as both clamping and lock nuts. The other circuit terminal may be connected 35 to the engine body at any appropriate point after the usual practice. The spark then passes between the teeth 20 and the annular end 21 of the body 7. By this means there is little or no danger of choking or short circuiting at the spark terminals since there are 40 a large number of points for the sparks to pass, and should one become burned off others remain and so the life of the terminals is much prolonged. It is found that the disk 45 19 will successfully operate when made of German silver.

With a device such as described, the member 1 is screwed into the spark plug receiving passage of the ignition chamber and may 50 remain in such passage permanently. The removable member of the spark plug may then be inserted by causing the pins 8 to enter the slots 3 and by a slight twisting motion through an arc of about ninety degrees, more or less, the movable member is firmly seated in the fixed member 1. The cam action of the slots 3, which are suitably shaped for this purpose, will so firmly seat the movable member in the fixed member that the joint is rendered gas tight, even under the high pressures generated in the explosion chamber when the charge is fired. This is easily accomplished by properly grinding the meeting surfaces of the cones of the movable 65 and fixed members. When it becomes neces-

sary to remove the plug the operator has but to apply a twisting force to the handles 9 in a direction at right angles to the longitudinal axis of the plug and the movable member is immediately forced out of its seat and may 70 then be lifted from the open ends of the slots 3, no tools of any kind being necessary for this purpose. It is to be further observed that the movable member of the plug carries both spark terminals and, therefore, inspection 75 or repair of the vital portions of the spark plug is possible without the necessity of removing any parts by means of tools. Furthermore, the fixed member may be properly packed against leakage when first put in 80 place and need not, therefore, be disturbed.

What is claimed is:—

1. A spark plug comprising a fixed member provided with open ended cam slots terminating at their inner ends in plane portions concentric with the longitudinal axis of the said fixed member and extending entirely through the walls of the fixed member throughout their length, and a removable member carrying both terminals of the spark 85 circuit and provided with means for engaging the walls of the cam slots to be thereby seated and locked in the fixed member when the engaging means are in the plane portions of the said cam slots, the said engaging means 90 on the removable member extending entirely through the said cam slots and there provided with manipulating handles.

2. A spark plug comprising a fixed member composed of a cylindrical body having a threaded neck at one end, and open-ended cam slots at the other end, said cam slots entering said end of the cylindrical body, and then curving and ending in plane portions concentric with the longitudinal axis of the 100 cylindrical body, the latter being also provided with an interior conical seat, and a removable member having a conical portion adapted to said seat and carrying both spark terminals, said removable member also being provided with handles having portions adapted to enter the cam slots, and to engage the walls of the latter to seat the removable member in the fixed member and to lock the two together when the handles are in the 105 plane portions of the said cam slots.

3. A spark plug comprising a cylindrical member having a threaded neck at one end and an interior conical seat, and at the other end having open-ended cam slots entering the said end of the cylindrical member and then curving and ending in plane portions concentric with the longitudinal axis of said cylindrical member, a removable member composed of a body portion having a conical section adapted to the conical seat in the fixed member and also provided with a longitudinal central passage, radial pins carried by the body of the removable member and adapted to enter the slots of the fixed mem- 110 115 120 125 130

ber and locking in the plane portions of the said slots, a conducting stem central to the removable member and insulated therefrom, means for locking said stem to the removable member, and a circuit terminal carried by the stem in operative relation to the inner end of the body of the removable member.

In testimony that I claim the foregoing as my own, I have hereto affixed my signature in the presence of two witnesses.

THEODOR WINESTOCK.
